UNITED STATES PATENT OFFICE.

CHARLES S. ASH, OF GENEVA, NEW YORK.

METHOD OF MAKING WHEEL HUBS.

Application filed August 10, 1918, Serial No. 249,279. Renewed March 16, 1923.

To all whom it may concern:

Be it known that I, CHARLES S. ASH, a citizen of the United States, residing at Geneva, in the county of Ontario and State 5 of New York, have invented certain new and useful Improvements in Methods of Making Wheel Hubs, of which the following is a full, clear, and exact description, such as will enable others skilled in the art to which 10 it appertains to make and use the same.

This invention relates to methods of making wheel hubs, and is more particularly directed to improvements in hubs designed for wire-spoked wheels and to an improved 15 method of manufacture thereof.

It is one of the objects of the invention to provide an improved hub of the character mentioned especially adapted for airplanes and possessing the qualities of lightness and 20 strength in an augmented degree.

A further object is to provide an improved and simplified method of forming such hubs of drawn metal whereby the cost is decreased and the manufacture thereof is 25 facilitated.

Other objects and advantages will be in part noted hereinafter in connection with the following description of the accompanying 30 drawings, which illustrates an exemplary, preferred embodiment of the invention, and in which—

Figure 1 is a longitudinal central sectional view of the improved hub;

Fig. 2 is a fragmentary sectional view of 35 metal tubing from which the hub may be made;

Fig. 3 is a similar view showing the end of the tube expanded in one step of manufacture;

Fig. 4 is a similar view showing the extreme end outturned to provide spoke flanges in another step of manufacture;

Fig. 5 is a similar view showing the inner walls bored in another step of manufacture;

Fig. 6 is a sectional view of a flat disc from which the tube may be drawn;

Fig. 7 is a fragmentary sectional view of the same in one stage of drawing; and

Fig. 8 is a sectional view of the drawn 50 tube which may be finished as shown in Figs. 2, 3 and 4.

According to the present invention, the hub is made of drawn metal and may be fashioned from seamless tubing or be drawn 55 from the flat, as is known to the art. Refer-

ring more specifically to Figs. 3-5 of the drawings, a unit section of metal tube 1 of the desired length and having uni-dimensional walls of suitable thickness is first provided.

In the next step of operation the two ends of the tubing are expanded, by the use of dies or otherwise, to provide integral end walls 2 of substantially unaltered thickness, but with an interior bore diameter, indicated 60 at 3, somewhat greater than the bore diameter, at 4, of the remaining intermediate unexpanded portions 5. It will be understood that the resultant unit having the two-dimensional diameters, may also be achieved 65 by employing initially a tubing of increased diameter (as indicated at 3 in Fig. 3), and thereafter contracting the intermediate walls by swaging or otherwise to provide the lesser diameter (indicated at 4 in Fig. 70 3). In practice, the length of each expanded end wall 2 may be preferably approximately one-quarter to one-fifth the length of the unexpanded intermediate section of the tubing, identified by the numeral 5 in Fig. 1. 75

In the next step of manufacture the extreme ends of the expanded wall portions 2 are outturned, also by dies or otherwise, to provide flanges 6 inclined backwardly at a 80 slightly acute angle to the axis of the tubing, for a purpose hereinafter described. The radial dimension of flanges 6 may substantially equal the axial length of the remaining portion of the expanded walls 2. The structure as thus presented conforms in general 85 to the completed hub, but a final step is employed in the operation to render the axial bore through the tubing of uniform diameter. Accordingly, as shown in Fig. 5 and indicated in dotted lines in Fig. 4, the tubing 90 is reamed to cut away a portion of the inner walls of the unexpanded section 5, and preferably, also, a slight surface from the axially 95 expanded walls 2, to provide a smooth inner bore extending throughout the tube and of a single uniform diameter. This operation 100 further results, as shown in Fig. 5, in decreasing the thickness and consequently the weight of the intermediate hub walls 5, while retaining substantially the original thickness of the tubing for the spoke flanges and the adjacent body walls, whereby the latter are of adequate strength to resist any strains imposed thereon.

For final adaptation of the hub as thus 110

made to assembly or association with the remaining parts of the wheel, bushings 8 or other forms of bearings are seated in the ends of the tubing. The flange 6 is also punched to provide spaced apertures 9 to receive the ends of wire spokes 10 leading therefrom by suitable lacing to the tire-carrying rim. As above mentioned, the spoke flanges 6 are turned backwardly to a 10 degree so that the plane thereof will be substantially parallel to the plane of the spokes 10 attached thereto, whereby the strain between the parts is substantially rectilinear.

Referring to Figs. 6, 7 and 8, there is 15 shown a method of working a flat metal disc into tubular form adapted for finishing into the hub structure. That is, a disc 11 is worked by successive drawing operations (an intermediate stage being indicated in 20 Fig. 7) into a tube (Fig. 8) having an upper end flange 12 and a closed end 13. By thus cutting open the lower end, the further drawing and boring operations, as above described, may be carried out, with expansion 25 of the end walls, finishing and inclining the spoke flanges, and machining the bore to render it of uniform diameter, as shown in the hub of Fig. 1.

It may be stated that hubs of the construction described and made in accordance with the foregoing method combine the qualities of strength and lightness to a degree which renders them peculiarly advantageous for airplanes, and further that such 30 hubs of drawn metal are capable of expeditious manufacture at a very material decrease of cost as compared with the hubs heretofore commonly used for a similar purpose.

40 As many changes could be made in carrying out the above method without departing from the scope of the invention, it is intended that all matter contained in the above description shall be interpreted as illustrative and not in a limiting sense.

Having described my invention, what I claim as new and desire to secure by Letters Patent is:

1. The method of making a wheel hub, 50 which includes expanding the walls of a metal tube at its end to increase the end bore diameter, and then cutting away the inner

walls of the unexpanded portion of the tube to increase the bore diameter thereof.

2. The method of making a drawn metal 55 wheel hub of tubing, which includes altering the inner and outer diameters of part of the tube with respect to the remainder to provide an end bore diameter greater than the intermediate bore diameter, and then 60 cutting away the inner walls of the intermediate part to increase correspondingly the intermediate bore diameter.

3. The method of making a wheel hub, 65 which includes expanding the walls of the metal tube at its ends to provide relatively increased end bore diameters, outturning the end parts of such expanded walls to provide spoke flanges, and then cutting away the inner walls of the unexpanded portion of 70 the tube to provide a substantially uniform bore therethrough, with the end walls adjacent said flanges of greater thickness than the intermediate walls.

4. The method of making a drawn metal 75 wheel hub, which includes altering substantially equally the inner and outer diameters of predetermined portions of the length of a metal tube with respect to the remainder to provide end bore diameters greater than the 80 intermediate bore diameter, then outturning the ends of the tube to provide spoke flanges with adjacent tubular walls of the greater bore diameter, and finally cutting away the inner walls of the length having lesser bore 85 diameter to provide a substantially uniform bore diameter therethrough, with the spoke flanges and adjacent end walls of a thickness greater than the thickness of the intermediate walls.

5. The method of making a wheel hub, 90 which includes working flat stock into substantially tubular form with expanded ends, and then machining the inner walls to provide a bore of uniform diameter therethrough with middle walls of relatively lesser thickness than the end walls.

In testimony whereof I affix my signature, in the presence of two witnesses.

CHARLES S. ASH.
